US0D1105647S

(12) **United States Design Patent** (10) **Patent No.:** **US D1,105,647 S**
(45) **Date of Patent:** **** Dec. 9, 2025**

(54) **CASTRATION TOOL**

(71) Applicant: **Jodi Allison Suchoplas**, Durban (CA)

(72) Inventor: **Jodi Allison Suchoplas**, Durban (CA)

(**) Term: **15 Years**

(21) Appl. No.: **29/908,918**

(22) Filed: **Jan. 16, 2024**

(51) LOC (15) Cl. **30-03**

(52) U.S. Cl.

USPC **D30/199**

(57)

CLAIM

The ornamental design for a castration tool as shown and described.

DESCRIPTION

FIG. 1 is a perspective view from a first end of a castration tool;

FIG. 2 is a perspective view thereof from an opposite end thereof;

FIG. 3 is a plan view thereof;

FIG. 4 is a side view thereof;

FIG. 5 is a first end view thereof; and,

FIG. 6 is an opposite end view thereof.
